CLAIM

The ornamental design for an eccentric shaft for a grinding machine, as shown and described.

DESCRIPTION

FIG. 1 is a perspective view of an eccentric shaft for a grinding machine showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a perspective view showing the eccentric shaft in environmental structure.

The broken lines depict portions of the eccentric shaft that form no part of the claimed design.

The dot-dashed lines in FIG. 7 of the eccentric shaft for a grinding machine is for the purpose of illustrating environmental structure for the claimed design and form no part of the claimed design.

1 Claim, 5 Drawing Sheets
